UNITED STATES PATENT OFFICE.

ALEXANDER FISCHER, OF BERLIN, GERMANY.

ELECTRIC ACCUMULATOR-PLATE.

SPECIFICATION forming part of Letters Patent No. 708,334, dated September 2, 1902.

Application filed June 21, 1902. Serial No. 112,624. (No model.)

To all whom it may concern:

Be it known that I, ALEXANDER FISCHER, a subject of the King of Prussia, residing at Berlin, in the Kingdom of Prussia, in the German Empire, have invented new and useful Improvements in Electric Accumulator-Plates, of which the following is a specification.

My present invention relates to improvements in electric accumulator-plates consisting of sheets of lead folded into serpentine form; and the objects of my improvements are, first, to stiffen such plates—that is, prevent the same from being straightened out in any degree—and, second, to increase their active surface. I attain these objects by the constructions of plate shown in the accompanying drawings, in which—

Figure 1 is a front elevation, and Fig. 2 a side elevation, of one construction of the plate; Fig. 3, a side elevation on the line A B of Fig. 1; Fig. 4, a side elevation, and Fig. 5 a front elevation, of the same plate on a larger scale; Fig. 6, a cross-section on the line C D. 25 of Fig. 5, while Fig. 7 is a front elevation, and Fig. 8 a cross-section, of another construction of the plate.

Similar letters refer to similar parts throughout the several views.

30 In carrying out my invention I bend or corrugate a plate *a* of lead to produce a number of relatively deep parallel grooves *b*. At the apex *c* of each corrugation I cut out a number of tongues *d*, in this way producing the openings *e* for the passage of the electrolyte. Along the top and bottom edge of the plate I provide a bar or rod *f* and *g*, respectively, in order to stiffen the plate laterally. The framework of the plate is now finished. It 35 can now be formed and then provided with the active mass or first provided with the active mass and then formed.

The grooves *b* are best formed by placing a strip of cardboard or the like of suitable 45 thickness in each groove, so that the distance between the same is maintained. This can, however, also be done by first placing a sheet of cardboard on each side of the metal sheet and by then folding the metal sheet and cardboard together. When the folding is com-

pleted, the cardboard can be removed in any suitable manner—for example, by means of concentrated sulfuric acid.

To produce the tongues, I may use any suitable form of apparatus. I prefer, however, to employ a two-part press provided with a number of parallel knives or cutters corresponding with the number of the tongues to be formed. The plates are placed singly or together in this press, and the knives are then 55 pressed into the plates and moved in the direction of the length of the grooves to an extent corresponding to the desired length of the tongues to be formed. In this manner the tongues are simultaneously cut and bent 60 outward. The tongues can be produced on both sides of the plates at the same time, or first on one side and then on the other.

Instead of moving the knives the press holding the plates may be moved. Further, I may 65 employ a single row of knives alone or one long knife, arranging the plate to be moved step by step to cut each tongue.

The construction shown in Figs. 7 and 8 only differs from that above described by the 70 employment of the stiffening-pieces *h*. As evident from the drawings, these pieces are folded with the plate and are spaced at intervals in the height thereof.

What I claim, and desire to secure by Letters Patent of the United States, is—

1. Accumulator-plate comprising in combination: a plate of lead folded into serpentine form; tongues cut out of said plate at the apex of each fold and bent outward; and active mass disposed between said folds; substantially as set forth. 80

2. The combination with a serpentine-folded accumulator-plate of tongues cut out of said plate at the apex of each fold and bent 85 outward; substantially as set forth.

3. The combination with a serpentine-folded accumulator-plate of tongues cut out of said plate at the apex of each fold and bent outward, and stiffening-pieces folded with 90 said plate at intervals in the height thereof; substantially as set forth.

4. The method of producing accumulator-plates which consists in: (1) folding a sheet of lead into serpentine form; (2) cutting tongues 95

out of said plates at the apex of said folds and bending said tongues outward; substantially as set forth.

5. The method of producing accumulator- plates which consists in: (1) folding a sheet of lead into serpentine form; (2) cutting tongues out of said plate at the apex of said folds and bending said tongues outward; filling the grooves of said plate with active mass; and

giving the plate the desired shape; substantially as set forth.

In testimony whereof I have signed my name to this specification in the presence of two subscribing witnesses.

ALEXANDER FISCHER.
